To all whom it may concern:

Be it known that we, Alfred B. Girardy, Clarence V. Norby, and Donald W. Doman, citizens of the United States of America, and residents, respectively, of Park Forest, county of Cook, and State of Illinois, Chicago, county of Cook, and State of Illinois, and Harvey, county of Cook, and State of Illinois, have invented a new, original, and ornamental Design for a Railway Car Body, of which the following is a specification, reference being had to the accompanying drawings forming part thereof.

In the drawings:

Fig. 1 is a general perspective view of a railway car body in which our new design is incorporated, having portions broken away better to reveal the disposition of the observation lounge within the vehicle, and indicating the supporting trucks in dotted lines;

Fig. 2 is a horizontal mid-sectional view taken through the vehicle showing the observation lounge;

Fig. 3 is a vertical longitudinal sectional view through the vehicle showing the observation lounge, taken on the line 3—3 of Fig. 2;

Fig. 4 is a vertical transverse sectional view through the entire vehicle body showing the observation lounge, taken substantially as indicated by the line 4—4 of Fig. 3;

Fig. 5 is a perspective view of one end portion of the observation lounge in the railway car body; and Fig. 6 is a perspective view of the other end of the observation lounge in the railway car body.

The characteristic features of the present design reside in the interior observation lounge shown in the drawings.

We claim:

The ornamental design for a railway car body, substantially as shown and described.
